UNITED STATES PATENT OFFICE.

RICHARD HOELEMANN, OF NEW YORK, N. Y.

SAFETY-LATCH FOR PRESSES.

1,319,078.

Specification of Letters Patent.

Patented Oct. 21, 1919.

Application filed June 14, 1916. Serial No. 103,636.

To all whom it may concern:

Be it known that I, RICHARD HOELEMANN, a citizen of the United States, residing in the city of New York, county of Queens, and 5 State of New York, have invented certain new and useful Improvements in Safety-Latches for Presses, of which the following is a specification.

My invention relates in general to a safety 10 device for use in connection with a clutch mechanism and while the invention is applicable to any mechanism where it is desired to limit the duration of the active operation of the clutch, the invention particularly relates to a safety attachment for 15 punch presses and similar machinery where it is desired that the clutch be moved into active position for one operation of the machine and stopped automatically at the end 20 of its desired period of operation.

In power presses it is usual for the operator to inaugurate the actuation of the machine by pressing upon a foot treadle or similar starting device and one of the objects of the invention is to provide, a simple, durable, and reliable safety mechanism 25 designed to constitute an attachment to conventional forms of such machines and which will positively move the clutch mechanism into inoperative position at the termination 30 of one actuation of the machine and independently of the position of the treadle or manual control mechanism.

Incidental to an object of simplicity in 35 design it is a further desideratum of this invention to provide a device of the class described with the least possible number of parts and which may be constructed with a minimum amount of machining, so as to 40 provide a construction which can be marketed at low cost.

Another object of the invention is to provide a safety device which is not only susceptible of being installed on conventional 45 forms of press machines, but which is desired, may be readily removed for replacement or repair without interrupting the continuous operation of the machine during the period when the safety device is removed.

50 Still another object of the invention is to provide a safety device in the form of an attachment, which may be made of some standard form and provided with means for readily adjusting the same to fit different 55 makes of machine.

Various other objects and advantages of

the invention will be in part obvious from an inspection of the accompanying drawings and in part will be more fully set forth in the following particular description of 60 one form of mechanism embodying my invention, and the invention also consists in certain new and novel features of construction and combination of parts hereinafter set forth and claimed.

65

Referring to the accompanying drawings: Figure 1 is a view in side elevation of a portion of a power press showing a form of clutch mechanism used with such machines and shown in locking position and showing 70 a preferred embodiment of my invention in normal inoperative position thereon with parts thereof broken away to show internal construction;

Fig. 2 is a transverse sectional view taken 75 on the broken line 2—2 of Fig. 1; and

Fig. 3 is a view in side elevation of certain of the parts shown in Fig. 1, showing the safety attachment in active clutch locking 80 position.

In the following description and in the claims, parts will be identified by specific names for convenience of expression but they are intended to be as generic in their application to similar parts as the art will 85 permit.

In the drawings there is shown a clutch wheel 4 loosely mounted upon the crank shaft 5 and a clutch member 6 including the projecting rocker arm 7, normally moved 90 into clutching position by the rocker arm spring 8 as is usual with one well known type of clutch mechanism. It is usual in such machines to hold the rocker arm in its unclutched or inoperative position by means 95 of a trip dog 9 pivotally mounted upon a pivot bolt 10 carried in a bracket 11 and moved into unlatched position by means of a treadle rod 12 controlled by the foot or hand of the operator. Such devices also include a relatively strong treadle rod spring 13 designed to move the trip dog into its locking position disposed across the path of movement of the rocker arm when pressure is released on the treadle rod. It is to be 100 understood that the construction so far described is well known and the invention hereinafter described particularly relates to an attachment designed to be mounted upon the pivot bolt 10 which is elongated to accommodate the attachment.

The attachment includes a rocker frame

- 14, the upper end of which is provided with a projecting finger 15 constituting a stop similar to the usual trip dog and designed, when the rocker arm is in its normal position held by the trip dog, to bear against the side of the rocker arm so that normally the rocker arm constitutes a stop for maintaining the projecting finger 15 in an inoperative position as shown in Figs. 1 and 2.
- 10 The rocking frame includes a depending tail 16, threaded through which is a set screw 17, locked in position by the lock nut 18 and designed to bear against some suitable stop 19, which, in the device disclosed, 15 may be some fixed part of the machine. The rocking frame also includes a kicking device 20 positioned above the bolt 10 for the purpose of moving the finger 15 into active position when released by the rocking arm.
- 20 This kicking device includes a plunger 21 slidably mounted in a spring casing 22 demountably affixed to the rocking frame preferably by screws 23 to permit the ready separation of the plunger and its coacting parts 25 for the purpose of repair or substitution for another kicking device. The plunger 21 is maintained normally in projected position toward the stop 19 by means of a spring 24 housed within the casing 22 but obviously 30 having a tension less than the tension of the treadle rod spring 13. The plunger is designed to be set in adjusted position by lock nuts 25 engaging the rear threaded end 26 of the plunger which projects rearwardly 35 from the casing 22.
- The tension of the treadle rod spring 13 is transmitted to the rocking frame through an adjustable stop 27, in the form of a set screw locked in adjusted position in a rearward extension 40 from the portion of the locking frame above its fulcrum. This set screw is disposed in the path of the upward movement of the treadle rod, so that as tension is released on the treadle rod, the spring in re- 45 setting the dog in the position shown in Fig. 1, will bear on the set screw 27 to move the rocking frame from the position shown in Fig. 3 into the upright position shown in Fig. 1.
- 50 In operation, it will be understood that the clutch wheel 4 is rotating continuously and that when it is desired to actuate the crank-shaft 5, the operator depresses the treadle rod, thus swinging the trip dog from the position shown in Fig. 1 into the position 55 shown in Fig. 3, thus removing the dog from the path of movement of the rocker arm and at the same time placing the heavy treadle rod spring under tension, all as is usual with well known devices of this character.
- The removal of the rocker arm from the path of swinging movement of the projecting finger 15 will permit the spring 24 to 60 act on the plunger bearing against the stop

19 and thus re-act on the rocker frame to move the same into the set position shown in Fig. 3 or until the end of the set screw 17 comes in contact with its stop 19. This set screw has previously been so adjusted that the projecting finger 15 is now disposed in 75 the path of movement of the rocker arm so that as the rocker arm rotates about in its shaft clutching position, it will now come in contact with the projecting finger disposed in its path with the result that the rocker arm is rocked against the tension of its holding spring and the clutch wheel thus automatically disconnected from the crank-shaft. It will be noted that this automatic 80 unclutching by the auxiliary stop finger 15 will take place independent of the position on the treadle rod, so that the operator by pressing on the treadle will cause but one actuation of the crank-shaft and the second 85 stop 15 will automatically cause the clutch to be moved into inoperative position at the end of one rotation of the crank-shaft. By adjusting the set-screw 17 the attachment 90 may be held in inoperative position which will not affect the usual operation of the machine.

Releasing tension on the treadle rod will cause the heavy spring 13 to act on the trip dog moving the same back into its operative 95 position and acting through the set screw 27 on the rocker frame to move the same into its normal position shown in Fig. 1. At the same time the plunger spring 24 is placed under compression by the depression 100 of the plunger bearing on the stop 19. This action removes the projecting finger 15 from the path of movement of the rocker arm and permits the rocker arm to move slightly 105 into position stopped by the trip dog and the device is in position for a repetition of the actuation of the machine.

By means of a device of this character it is possible to install a safety device on conventional forms of press machines merely by 110 substituting a longer bolt for the bolts usually used to pivotally support the trip dog. These safety devices may be sold as simple articles of manufacture and utilized as attachments to the several different forms of 115 machines, as desired. With the different machines it will be found that the stop 19 provided by the machines are differently spaced from the bolt carrying the trip dog but the several set screws carried by the attachment may be adjusted to fit any particular machine. The attachment may be readily removed and the machine actuated as usual without a safety device and the fact that the conventional forms of machines, 120 need not be modified in any way to receive the safety device constitutes one of the important features of this invention.

While I have shown and described, and have pointed out in the annexed claims, cer- 130

tain novel features of my invention, it will be understood that various omissions, substitutions and changes in the form and details of the device illustrated and in its 5 operation may be made by those skilled in the art without departing from the spirit of the invention.

Having thus described my invention, I claim:

- 10 1. In a device of the class described, the combination with a revolving rocker arm and a pivotally mounted trip dog normally disposed in the path of the rocker arm to intercept its movement and manually actuated means acting directly on said trip dog to move the same into inoperative position, of a supplemental stop normally held in inoperative position by the rocker arm, and means normally acting on said supplemental 15 stop to cause it to be positioned in the path of said revolving arm thereby to intercept its movement.
- 20 2. In a device of the class described, the combination with a revolving rocker arm and a trip dog normally disposed in the path of the rocker arm to intercept its movement and means having a movement independent of the trip dog and movable automatically into operative position to limit the movement of the rocker arm upon the release of the trip dog and a pivotal mounting for both the trip dog and for said limiting means.
- 25 3. In a device of the class described, the combination with a clutch and manually controlled means for holding the clutch in an inoperative position, a pivot bolt, a supplemental stop normally held in an inoperative position by the held clutch rotatably mounted on said bolt and resilient means independent of the manually controlled means for moving the stop into position to hold the clutch.
- 30 4. In a device of the class described, the combination with a clutch and manually controlled means for holding the clutch in an inoperative position, a supplemental stop normally held in an inoperative position by the held clutch and resilient means carried by the stop and movable bodily therewith for moving the stop into position to hold the clutch, said resilient means being operable automatically on the release of the manually controlled means.
- 35 5. In a device of the class described, the combination with a clutch mechanism having a definite path of travel, of a pair of stop members each pivoted for movement about a common axis and each movable across the path of the clutch mechanism to intercept the movement of the same, said mechanism normally held by the most advanced of the pair of stop members and said mechanism when in held position disposed in the path of movement of the other stop member, means for moving said advanced stop member from the path of the clutch mechanism thereby to permit the release of the clutch mechanism and automatically actuated means acting on the other stop member for 40 moving this member into the path of the clutch mechanisms to intercept the movement of the same irrespective of the position of the most advanced stop member.
- 45 6. In a device of the class described, the combination with a clutch mechanism having a definite path of travel, of a pair of stop members each pivoted for movement about a common axis and loosely mounted relative to each other and each movable across the path of the clutch mechanism to intercept the movement of the same, said mechanism normally held by the most advanced of the pair of stop members and said mechanism when in held position disposed in the path of movement of the other stop member, means for moving said advanced stop member from the path of the clutch mechanism thereby to permit the release of the clutch mechanism and means acting 45 on the other stop member for moving this member automatically into the path of the clutch mechanism on the release of the most advanced stop member.
- 50 7. In a device of the class described, the combination with a clutch mechanism having a definite path of travel, of a pair of stop members loosely mounted relative to each other, each movable across the path of the clutch mechanism to intercept the movement of the same, said mechanism normally held by the most advanced of the pair of stop members and said mechanism when in held position disposed in the path of movement of the other stop member, means for moving said advanced stop member from the path of the clutch mechanism thereby to permit the release of the clutch mechanism, means acting on the other stop member for moving this member automatically 55 into the path of the clutch mechanism on the release of the most advanced stop member and adjustable means for varying the length of movement of said other stop member during its automatic movement.
- 55 8. In a device of the class described, the combination with a clutch mechanism having a definite path of travel, of a pair of stop members each pivoted for movement about a common axis and each movable across the path of the clutch mechanism to intercept the movement of the same, said mechanism normally held by the most advanced of the pair of stop members and said mechanism when in held position disposed in the path of movement of the other stop member, means for moving said advanced stop member from the path of the clutch mechanism thereby to permit the release of the clutch mechanism, means acting on the 60 120
- 60 9. In a device of the class described, the combination with a clutch mechanism having a definite path of travel, of a pair of stop members each pivoted for movement about a common axis and each movable across the path of the clutch mechanism to intercept the movement of the same, said mechanism normally held by the most advanced of the pair of stop members and said mechanism when in held position disposed in the path of movement of the other stop member, means for moving said advanced stop member from the path of the clutch mechanism thereby to permit the release of the clutch mechanism, means acting on the 65 125
- 65 10. In a device of the class described, the combination with a clutch mechanism having a definite path of travel, of a pair of stop members each pivoted for movement about a common axis and each movable across the path of the clutch mechanism to intercept the movement of the same, said mechanism normally held by the most advanced of the pair of stop members and said mechanism when in held position disposed in the path of movement of the other stop member, means for moving said advanced stop member from the path of the clutch mechanism thereby to permit the release of the clutch mechanism, means acting on the 130

other stop member for moving this member automatically into the path of the clutch mechanism on the release of the most advanced stop member and means for resetting 5 both of said stop members.

9. In a device of the class described, the combination, with a clutch member having a definite path of movement, of a pair of stop members each pivoted for movement 10 about a common axis and each movable across said path of movement to intercept the movement of the clutch member, manually controlled means for removing one of said stop members from its operative position 15 thereby to permit the release of the clutch member and means acting on the other stop member to move the same into intercepting position into said path, said last named means designed to become active on the release of the clutch member.

10. In a device of the class described, the combination, with a clutch member having a definite path of movement, of a pair of stop members, each movable across said path 20 of movement to intercept the movement of the clutch member, manually controlled means for removing one of said stop members from its operative position thereby to permit the release of the clutch member, 25 means acting on the other stop member to move the same into intercepting position into said path, said last named means designed to become active on the release of the clutch member and means for regulating the 30 movement of said other member to and from its operative position.

11. A device of the class described, comprising a pivoting member, a trip dog pivoted 40 to said member, a rocking frame pivoted to said member, said frame including a stop finger, and a kicking device carried by the frame and designed to move the same into an operative position.

12. A device of the class described, comprising a pivoting member, a trip dog pivoted 45 to said member, a rocking frame pivoted to said member, said frame including a stop finger, a kicking device carried by the frame and designed to move the same into 50 an operative position and means carried by the trip dog for engaging with the rocking frame to reset the same.

13. A device of the class described, comprising a pivoting member, a trip dog

pivoted to said member, a rocking frame 55 pivoted to said member, said frame including a stop finger, a kicking device carried by the frame and designed to move the same into an operative position and means carried by the trip dog for engaging with the rocking 60 frame to reset the same and to energize said kicking device.

14. In a device of the class described, a support, a pivoting bolt carried by said support, a tripping dog pivoted to said bolt, a 65 rocking frame pivoted to said bolt, a spring pressed plunger carried by the frame and designed to kick the frame into an operative position when released, and resilient means reacting between said support and dog to 70 reset the dog and frame into normal position and to place the plunger under tension.

15. In a device of the class described, the combination with a clutch mechanism, and 75 two stop members, means for pivotally supporting said members, each designed to intercept the movement of the clutch mechanism, manually controlled means for moving 80 one of the stop members into an inoperative position to permit the escape of the clutch mechanism and means controlled by the escape of the clutch mechanism for moving the other stop member automatically into 85 an operative position independent of the position of the manually controlled means.

16. In a device of the class described, the combination with a clutch mechanism, and two stop members, means for pivotally supporting said members, each designed to intercept the movement of the clutch mechanism, manually controlled means for moving 90 one of the stop members into an inoperative position to permit the escape of the clutch mechanism, means controlled by the 95 escape of the clutch mechanism for moving the other stop member automatically into an operative position independent of the position of the manually controlled means and means controlled by the release of the 100 manually controlled means for moving said other stop member into an inoperative position and resetting the first named stop member into operative position.

Signed at New York city in the county of 105 New York and State of New York this twelfth day of June A. D. 1916.

RICHARD HOELEMANN.
